(57) **CLAIM**

We claim the ornamental design for a harness attachment hook, as shown and described.

DESCRIPTION

This application is related to application Ser. No. 16/808,171 filed of even date herewith.

FIG. 1 is a perspective view of the claimed harness attachment hook according to an exemplary embodiment; FIG. 2 is a side view of the embodiment of FIG. 1; FIG. 3 is another side view of the embodiment of FIG. 1; FIG. 4 is a rear view of the embodiment of FIG. 1; FIG. 5 is a front view of the embodiment of FIG. 1; FIG. 6 is a top view of the embodiment of FIG. 1; and, FIG. 7 is a bottom view of the embodiment of FIG. 1.

Any portion of the article depicted in broken lines forms no part of the claimed design. Broken lines formed by equal length dashes show unclaimed portions of the design. Any shade lines in the drawings show contour and not surface ornamentation.
